TRANSFORMER INSULATION

Arthur W. Thompson, Sharon, Pa., assignor to
Westinghouse Electric & Manufacturing Com-
pany, East Pittsburgh, Pa., a corporation of
Pennsylvania

Application October 29, 1932. Serial No. 640,176

6 Claims. (Cl. 175—356)

My invention relates to insulation for electrical apparatus and particularly to the construction and arrangement of the insulating barriers associated with multiple coil transformer windings which utilize nested barriers of insulating material.

The improved barrier construction of my invention is particularly adapted for application to high-voltage oil-insulated surge-proof 10 transformers, although it may also be applied to low-voltage transformers or to air-insulated transformers. The invention is described more in detail as applied to shell-type transformers although the principles thereof are also applicable to core-type transformers.

In a copending application Serial No. 567,210 by Henry V. Putman, filed October 6, 1931 and assigned to the Westinghouse Electric and Manufacturing Company, there is described an improved arrangement of the various parts of a transformer winding and of the solid insulating material associated therewith which effects maximum dielectric strength for a given amount of insulating material. When constructed in accordance with the teachings of this application, a transformer is highly resistive to surge voltages. Such a transformer comprises windings made up of a number of flat coils of different sizes which are so insulated by a series of nested insulating 25 barriers that the number of layers of insulating material between any two points on the winding or between a point on the winding and ground is proportional to the voltage stress between these points. The insulating barriers, which are arranged to substantially follow the equipotential surfaces of the electrostatic fields of the winding coils, are so disposed that failure of the insulation can occur only by the puncture of the barriers and not by creepage along the barrier 30 surfaces.

In the construction of each of the barriers it has in the past been necessary to build up special washers, of a shape simulating that of the coil contour, by attaching to the main flat body 45 portion of the washer a plurality of angle pieces to form the required right-angle edge. Because of the excessive amount of labor involved in making the angle edges and suitably attaching them to the washer body, this form of construction has 50 proven unduly expensive, as well as not being completely effective from the standpoint of insulation strength and mechanical rigidity. My invention is directed to an improved form of construction for such washers which overcomes the 55 disadvantages named and which possesses further advantages to be particularized hereinafter.

Generally stated, the object of my invention is to simplify the construction of insulation for 60 transformers.

Another object of my invention is to reduce

the cost of assembling the insulating barriers in a transformer and to produce a simple and mechanically rigid barrier structure.

A further object of my invention is to provide 65 a barrier construction having improved insulation strength, particularly at the barrier corners.

An additional object of my invention is to provide an insulating barrier construction which will permit of free oil circulation between the 70 barriers and the winding coils with which they are associated.

More specifically stated, an object of my invention is to provide an improved and simplified form of construction for the end portions or 75 washer assemblies of the insulating material barriers utilized by transformers of the surge proof construction.

Fullerboard has been adopted as being satisfactory material for use in the construction of 80 insulating barriers for the windings of surge proof transformers, which material has had a very extensive application in the general field of transformer insulation. As is known, fullerboard is made from suitable wood pulp, which, 85 in a highly moistened or wet state is formed into sheets by being simultaneously subjected to heat and pressure, the original pulp being dried thereby into a homogeneous mass possessing considerable mechanical rigidity. When fullerboard is properly moistened, therefore, it may 90 revert to its original plastic or pulp-like condition thereby permitting the physical shape or contour of the moistened portions to be changed through an exceedingly wide range. A re-application 95 of heat and pressure may then be employed to restore the mechanical rigidity to the moistened portions to thereby cause the fullerboard to retain the modified physical form.

In practicing my invention, I utilize the above 100 described characteristic of fullerboard in turning up the edges of the main washer or end portion of the insulating barrier by moistening the edges of the washer and inserting them into a suitably formed and heated mould. By this 105 process I am able to construct fullerboard washers having edges turned up at an angle of substantially 90° and I thereby eliminate the necessity of attaching a large number of angle pieces to a main flat portion as has been necessary in 110 the past.

My invention will best be understood from the following description of specific embodiments thereof when taken in conjunction with the accompanying drawings in which:

Figure 1 is a view in horizontal section through 115 the windings and core of a shell-type transformer illustrating the coils and insulating barriers arranged in accordance with one embodiment of transformer construction to which the 120

improved washers of my invention are particularly applicable.

Fig. 2 is a sectional view of the transformer illustrated in Fig. 1 taken along line II-II 5 thereof.

Fig. 3 is a view of the high voltage winding assembly illustrated in Fig. 1 showing the manner in which the fullerboard washers of my invention are applied in building the nested insulating barriers about the winding coils.

Fig. 4 is a plan view, drawn to reduced scale, of one of the complete washers employed in the structure illustrated in Fig. 3.

Fig. 5 is a sectional view of the washer, taken 15 along the line V-V of Fig. 4, illustrating the turned-up edges of the washer.

Fig. 6 is a plan view of part of the washer illustrated in Fig. 4, showing certain details of construction thereof.

Fig. 7 is a plan view of one of the inserts that may be used on the inside corners of the washer of Figs. 4, 5 and 6.

Figs. 8 and 9 are plan and elevational views of a modified form of construction of the improved 25 washer in which only the outer edge is turned up.

Figs. 10 and 11 are similar views of a form of washer construction having only the inside edge turned up.

Figs. 12 and 13 are plan views illustrating the 30 manner in which a complete washer may be made up from a plurality of individually formed portions, and

Fig. 14 is a plan view of a circular form of 35 washer, having a turned up edge, that is suitable for use with core-type transformers.

Referring to the drawings, the arrangement of the core and coils of a shell type transformer is shown in Figs. 1 and 2. In these figures, the 40 core structure is shown as comprising two stacks of closed magnetic laminations 10 and 11, the adjacent sides of which form the winding leg of the transformer. The low voltage winding of the transformer is shown in two parts 16 and 17, 45 surrounding and adjacent opposite ends of the winding leg. Between the low voltage windings are placed coils 20 to 26, inclusive, forming the high voltage winding.

Insulating barriers 30 to 36, inclusive, are 50 shown in Fig. 1 in simplified form in the left-hand window of the core surrounding each of the several coils. For the sake of simplicity and to better show the connections between the coils, these insulating barriers are not shown in Fig. 55 1 in the right-hand window, that is, within the opening of the core structure 11, although it will be understood that they extend continuously about the several coils as indicated in Fig. 2. It will be noted that the coils proceeding from one 60 end of the winding toward the other end, that is, from coil 20 to coil 26, are of decreasing external dimensions and increasing internal dimensions to accommodate the barriers 30 to 36, inclusive.

In Figs. 1 and 2 the insulating barriers, 30 to 65 36 inclusive, have been represented in simplified form, no attempt being made to show the details of construction. Such details are shown in Fig. 3 in which only the portion of the high voltage winding coils 20 to 26, inclusive, included in the left-hand window of the core structure of Fig. 1 are illustrated. Each of the barriers, shown in Figs. 1 and 2 at 30 to 36, inclusive, is preferably constructed from fullerboard

70 75 and comprises a pair of washers of the general

type shown in Figs. 4 and 5 having turned-up edges. Thus, for example, in the case of the barrier 30 directly associated with coil 20, the two associated washers are shown at 30' and 30'', respectively, in Fig. 3, the turned-up edges 80 thereof being disposed to face each other so that the barrier may be completed by the sheets 40 and 42 of insulating material. The sheet 40 is overlapped by the outer edges of washers 30' and 30'' and will be seen, as reference to the simplified showing of Fig. 2 will indicate, to extend continuously around the outer periphery of coil 20. Likewise, the sheet 42 is overlapped by the inner edges of the washers 30' and 30'' and will be seen to extend continuously around the inner periphery of coil 20.

The insulating barriers associated with coils 21 to 26, inclusive, will be seen to similarly comprise fullerboard washers having turned-up edges and cooperating portions of insulating material sheets so that further detailed description of them is deemed unnecessary.

As has been mentioned, each of these washers, one of which is illustrated by Figs. 4 and 5, is preferably constructed from fullerboard or comparable insulating material. Fig. 6 is a detailed view of one corner of the washer shown in Fig. 4 more clearly illustrating the manner of construction. A flat sheet of fullerboard is first cut to the dimensions indicated by the dotted 105 outline in Fig. 6. The edges of this sheet are moistened to reduce the material to a plastic form, and are then bent to the desired 90° angle, a suitably heated mould being applied to compress and dry the turned-up portion.

Due to the extreme change in contour of the fullerboard, at the inside corners of the washer, which such turning-up operation necessitates, and to avoid tearing the material, it has been found preferable to cut away a portion of the 115 horizontal inside edge, as at 50. The gap left at this corner may then readily be filled by the insertion therein of a special angle piece of the form illustrated in Fig. 7. This angle piece, which has a turned-up edge 52 shaped to exactly 120 conform to the inside turned-up edge of the main washer, is then applied to the corner, and by suitably moistening, heating and compressing is effectively bonded therein, the nature of fullerboard being such as to permit such a fusion of 125 its pulpy composition.

To provide for the flow of insulating oil between the windings of the transformer and the associated insulating barriers, suitable spacing means may be inserted therebetween as shown 130 in Fig. 3. In the case of winding coil 20 these spacing members are illustrated in the form of wavy spacers 60 and 61 placed on either side of the winding to separate it from direct contact with the surfaces of the adjacent barrier washers. In the plan view of one of the washers shown in Fig. 4 these wavy spacers are shown at 60', as attached to the inner surface of the washer. If desired, other spacing means, such as properly disposed rows of insulating material 140 blocks, may be substituted for these spacers the blocks have the advantage of allowing the oil to circulate in all directions rather than restricting the flow to one direction as do the wavy spacers illustrated.

In the showing of Fig. 3, the arrows are intended to indicate the paths available for oil flow. It will be noted that suitable ducts have been provided in the portions of the barrier intermediate the oppositely faced washers through 150

which the oil is permitted to pass. Preferably these ducts are staggered in the manner shown.

Instead of turning up both edges of the washer as shown in Fig. 4, it is possible to construct it in a manner that only one of the edges is turned up. Such a modified construction is illustrated in Figs. 8 and 9 in which a section of the washer is shown having only the outer edge thereof turned up. Figs. 10 and 11 illustrate a section of a washer having only the inner edge thereof turned up.

80
85

In certain instances it may be desired to build a double edge washer of the type shown in Fig. 4 in two separate sections each of which has only one edge thereof turned up. Thus, as shown in Fig. 12, the constructions of Figs. 8 and 10 may be combined to form the double edge assembly by properly fusing together the fullerboard material of the main flat portions of the sections as along the area shown as stippled in Fig. 12. The composition of fullerboard, as has been

90
95

pointed out, is such as to readily allow such fusion, the necessary operations being to moisten the sections to be joined, tightly compress them together and thoroughly dry under pressure. In this operation the use of a binding compound at the joint may be desired to improve the strength of the joint.

I claim as my invention:

1. In an electrical apparatus, the combination of a winding comprising a stack of coils and a series of insulating barriers each of which is arranged to enclose a different number of coils than the others, each of said barriers comprising a fullerboard washer having turned-up edges.

2. In an insulating barrier for a coil comprised by a multi-coil electrical winding, the combination of a plurality of insulating washers for the several coils each having contours corresponding to those of the coils, one continuous edge of each washer being permanently bent at a right angle to parallel one side of said coil.

100
105

3. In an insulating barrier for a coil comprised by a multi-coil electrical winding, the combination of a plurality of insulating washers for the several coils each having a main flat portion corresponding to the contour of the coil, the edges of said portion being bent at right angles to thereby parallel the sides of and thus surround said coil.

110
115

4. In an insulating barrier for a coil comprised by a multi-coil electrical winding, the combination of a fullerboard washer having a contour simulating that of the coil, one continuous edge of said washer being permanently bent at a right angle to parallel one side of said coil, said washer being built up from a plurality of 120 interfitting sections homogeneously merged together.

120
125

5. The method of manufacturing turned-up edge washers from sheet insulating material formed from pulp compressed and dried into a homogeneous mass, which consists in cutting from the sheet a piece of material having dimensions greater than those desired in the main flat portion of the completed washer, reducing the material along an area thereof to a pulpy state 130 by moistening, bending the material along said area to a desired angle, and simultaneously heating and compressing the material along the line of bend in said area to effect a drying thereof and a restoration of the material to its original mechanical rigidity.

130
135

6. The method of manufacturing turned-up edge washers from sheet fullerboard which consists in cutting from the sheet a piece of material having dimensions greater than those desired in 140 the main flat portion of the completed washer, reducing the fullerboard, along an area thereof, to a pulpy state by moistening, bending the material along said area to a desired angle, and simultaneously heating and compressing the 145 fullerboard along the line of bend to effect a drying thereof and a restoration of the material to its original mechanical rigidity.
